Inventor

Carl Schraubstadter Jr.

UNITED STATES PATENT OFFICE.

CARL SCHRAUBSTADTER, JR., OF ST. LOUIS, MISSOURI.

DESIGN FOR A FONT OF TYPE.

SPECIFICATION forming part of Design No. 25,899, dated August 4, 1896.

Application filed August 29, 1895. Serial No. 560,936. Term of patent 7 years.

To all whom it may concern:

Be it known that I, CARL SCHRAUBSTADTER, Jr., a citizen of the United States, residing at St. Louis, in the State of Missouri, have 5 invented and produced a new and useful Design for a Font of Printing-Type, of which the following is a specification, reference being had to the accompanying drawing, showing a part thereof.

10 The drawing shows a face view of a font of type comprising the upper and lower cases.

The leading features of my design consist in the font of type shown, comprising the main lines slightly hollowed out at the top 15 and bottom, as exemplified in such letters as the capitals H, I, N and lower-case m and n, and in the following letters: capital A, E, F, G, H, I, J, K, L, M, N, P, R, T, U, V,

W, X, and Z, short &, figures 2, 4, and 7, lower-case a, b, d, f, h, i, j, k, l, m, n, p, q, 20 r, s, t, u, v, w, x, y, and z. In certain other of the letters composed of straight and curved lines, the curved line meeting a vertical standard, the curve instead of ending at or before the straight line is continued beyond it, as exemplified at top and bottom of capital B and 25 D, top of capital P and R, bottom of lower-case a, b, and d, and top of lower-case p and q.

What I claim is—

The design for a font of printing-type, as 30 herein shown and described.

CARL SCHRAUBSTADTER, JR.
